ATTORNEY.

UNITED STATES PATENT OFFICE.

HOMER M. VICTOR, OF INDEPENDENCE, MISSOURI.

DESIGN FOR AN AUTOMOBILE-TOP.

54,708.

Specification for Design.

Patented Mar. 9, 1920.

Application filed September 8, 1919. Serial No. 322,565. Term of patent 14 years.

To all whom it may concern:

Be it known that I, HOMER M. VICTOR, a citizen of the United States, and a resident of Independence, county of Jackson, and State of Missouri, have invented a new, original, and ornamental Design for an Automobile-Top, of which the following is a specification, reference being had to the accompanying drawing, forming a part thereof.

In the said drawing:

Figure 1, is a side view of an automobile top embodying my invention.

Fig. 2, is a front view of the same.

Fig. 3, is a rear view of the same.

I claim:

The ornamental design for an automobile top as shown.

HOMER M. VICTOR.
